UNITED STATES PATENT OFFICE.

RICE D. SOPER, OF MARSHALL, MINNESOTA.

STOVE.

SPECIFICATION forming part of Letters Patent No. 443,337, dated December 23, 1890.

Application filed November 6, 1889. Serial No. 329,461. (No model.)

To all whom it may concern:

Be it known that I, RICE D. SOPER, a citizen of the United States of America, residing at Marshall, in the county of Lyon and State 5 of Minnesota, have invented certain new and useful Improvements in Stoves, of which the following is a specification, reference being had therein to the accompanying drawings.

This invention relates to certain improvements in cooking-stoves and hot-air heaters combined; and it consists in the novel construction and combination of parts herein-after disclosed.

In the accompanying drawings, Figure 1 is 15 a sectional elevation of my invention. Fig. 2 is a somewhat enlarged partly sectional and partly side view of a portion of said invention, parts also being broken away. Fig. 3 is a horizontal section taken on the line $y-y$ 20 of Fig. 1. Fig. 4 is a similar section taken on the line $z-z$ of Fig. 1. Fig. 5 is a like section taken on the line $w-w$ of Fig. 1, and Fig. 6 is also a like section taken on the line $x-x$ of Fig. 1.

25 In the embodiment of my invention I employ a fire-box or combustion-chamber A, suitably secured upon a base or hearth a, and in the bottom of this chamber or fire-box, above the hearth, is a grate B. The grate B consists of a series of circular hollow or tubular bars $b-b$, having communication with each other at short intervals by hollow or tubular connections $b'-b'$, and with the external air by means of air-inlet openings b .

35 The inner circular portion of the grate connects by a series of radial hollow arms b^3 with a central hot-air chamber or drum C at its bottom. Secure to the upper or top edges of the fire-box or combustion-chamber and the 40 drum C is the top plate A' of the said combustion-chamber or fire-box.

45 Encircling the combustion-chamber or fire-box is a casing or cylinder D extending some distance above the fire-box, and between them is an air-space into which external air is admitted through openings $c-c$, provided in said casing near its lower or bottom edge. Upon the outer vertical surface of the fire-box or combustion-chamber is secured a series of

50 spiral ribs $d-d$, dividing up the space between said chamber or fire-box and the casing D into a series of spiral passages, as shown.

In the upper part of the casing or cylinder D is the oven or cooking-chamber E, whose bottom E' rests a short distance above the 55 top of the combustion-chamber, providing a passage e .

The bottom E' has in it a series of perforations $h-h$ and a central opening i , opened and closed by a valve or damper j . In the top F 60 of the oven or cooking-chamber is a number of air-openings $g-g$, opened and closed by means of valves or dampers $g'-g'$ operated, either singly or in pairs, by rods g^2 , one secured to each valve, or to two valves, as shown, 65 as may be desired. These rods are guided in cleats or guides secured to the top F, while the valves themselves are suitably retained in position by means of flanges or cleats, also projecting from or secured to said top. 70

To the rear side of the casing or cylinder D is secured the stove-pipe collar k , having connection with the combustion-chamber, while also at a point farther up, opposite the ovens, is a similar collar l to permit the taking, 75 by means of a suitable pipe fitted thereon, of the hot air from the oven, and further utilizing it at a distant point—as, for instance, in heating an apartment or room.

To the upper end of the casing is supplied 80 a number of hot-air-exit valved nozzles g^3 , to which may be also applied pipes for conducting the hot air to an upper story or room or rooms.

Having thus fully described my invention, 85 what I claim, and desire to secure by Letters Patent, is—

1. In a combined cooking and heating stove, the fire-box having the spiral ribs on its outer surface dividing up the space between said 90 box and the outer casing or cylinder, the central hot-air chamber in said fire-box, the air-conducting grate, and the oven having the valves in its top and bottom, substantially as set forth. 95

2. In a combined cooking and heating stove, the fire-box or combustion-chamber having the spiral ribs on its outer surface dividing

up the space between said box and the outer casing or cylinder, the central hot-air chamber in said fire-box, the air-conducting grate, the oven having the valves in its bottom and 5 top, and the hot-air-exit valved nozzles applied to the top of said casing or cylinder, substantially as set forth.

In testimony whereof I affix my signature in presence of two witnesses.

RICE D. SOPER.
